US00D870971S

(12) **United States Design Patent** (10) Patent No.: **US D870,971 S**
(45) Date of Patent: **** Dec. 24, 2019**

(54) **RAZOR HANDLE**

(71) Applicant: **PCMR International Ltd.**, Beit She'an (IL)

(72) Inventors: **Michael Dubin**, Beverly Hills, CA (US); **Javier Hall**, Beverly Hills, CA (US); **Shlomo Zucker**, Beverly Hills, CA (US)

(73) Assignee: **Personal Care Marketing and Research, Inc.**, Marina Del Rey, CA (US)

(**) Term: **15 Years**

(21) Appl. No.: **29/639,847**

(22) Filed: **Mar. 9, 2018**

(51) LOC (12) Cl. **28-03**

(52) U.S. Cl.

USPC **D28/48**

(58) **Field of Classification Search**

USPC **D28/45-48**

CPC B26B 21/00-06; B26B 21/08-227; B26B 21/24-28; B26B 21/30-38; B26B 21/40-4093; B26B 21/52-528

(57) **CLAIM**

We claim the ornamental design for a razor handle, as shown and described.

DESCRIPTION

FIG. 1 is a front perspective of a razor handle according to an embodiment of our new design;

FIG. 2 is a left elevational view of a razor handle according to an embodiment of our new design;

FIG. 3 is a right elevational view of a razor handle according to an embodiment of our new design;

FIG. 4 is a top plan view of a razor handle according to an embodiment of our new design;

FIG. 5 is a bottom plan view of a razor handle according to an embodiment of our new design;

FIG. 6 is a front elevational view of a razor handle according to an embodiment of our new design; and,

FIG. 7 is a rear elevational view of a razor handle according to an embodiment of our new design.

1 Claim, 7 Drawing Sheets
